UNITED STATES PATENT OFFICE

118,973

DESIGN FOR AN AUTOMOBILE

Lucy E. Gilligan, Olean, N. Y.

Application January 3, 1940, Serial No. 89,275

Term of patent 14 years

To all whom it may concern:

Be it known that I, Lucy E. Gilligan, a citizen of the United States, residing at Olean, Cattaraugus County, State of New York, have invented a new, original, and ornamental Design for Automobiles, of which the following is a specification, reference being had to the accompanying drawings, forming a part thereof.

Fig. 1 is a front perspective view of an automobile showing my new design.

Fig. 2 is a side elevational view.

Fig. 3 is a front elevational view.

Fig. 4 is a rear elevational view, and

Fig. 5 is a top plan view.

While one side of the automobile is shown in Fig. 2, it will be understood that the opposite side is a duplicate of that shown in Fig. 2.

I claim:

The ornamental design for an automobile, as shown and described.

LUCY E. GILLIGAN.
